Michael J. Freemark, Breckenridge, Minn.

Application June 9, 1945, Serial No. 119,988

Term of patent 7 years

(Cl. D34—15)

To all whom it may concern:

Be it known that I, Michael J. Freemark, a citizen of the United States of America, residing at Breckenridge, in the county of Wilkin and State of Minnesota, have invented a new, original, and ornamental Design for a Helicopter Toy, of which the following is a specification, reference being had to the accompanying drawing, forming part thereof.

Referring to the drawing:

Fig. 1 is a top plan of a helicopter toy showing my new design;

Fig. 2 is a side elevation thereof; and
Fig. 3 is a front elevation thereof.

I claim:

The ornamental design for a helicopter toy, substantially as shown.

MICHAEL J. FREEMARK.
